UNITED STATES PATENT OFFICE.

FRANKLIN L. BARBER, OF CHICAGO, ILLINOIS, ASSIGNOR TO STANDARD CAR TRUCK COMPANY, OF CHICAGO, ILLINOIS, A CORPORATION OF NEW JERSEY.

JOURNAL-BOX TIE-STRAP.

1,115,886.

Specification of Letters Patent.

Patented Nov. 3, 1914.

Application filed July 13, 1914. Serial No. 850,590.

To all whom it may concern:

Be it known that I, FRANKLIN L. BARBER, a citizen of the United States, residing at Chicago, in the county of Cook and State 5 of Illinois, have invented certain new and useful Improvements in Journal-Box Tie-Straps; and I do hereby declare the following to be a full, clear, and exact description of the invention, such as will enable others skilled in the art to which it 10 appertains to make and use the same.

This invention relates to car trucks, and has for its object to provide an improved means for connecting the journal box tie 15 straps to the cast truck side frames.

In practice it has been found that the connection between the tie straps and side frames should be vertically adjustable, for the reason that the wheels, when worn down 20 and turned up, are considerably reduced in diameter, and as the wheels are successively turned and reduced in diameter, "shims" are placed on the tops of the journal boxes, so as to keep the car at the normal height 25 at the draw bar.

In the accompanying drawings, there are illustrated two schemes for connecting the tie straps to the side frames with freedom for vertical adjustments.

30 In the said drawings, like characters indicate like parts throughout the several views.

Referring to the drawings: Figure 1 is a view in side elevation with some parts 35 broken away, showing a cast truck side frame and a tie strap connected thereto, in accordance with this invention; Fig. 2 is an end elevation of the parts shown in Fig. 1; Fig. 3 is a view corresponding to Fig. 40 1 but illustrating a somewhat modified construction; and Fig. 4 is an end elevation of the parts shown in Fig. 3.

The cast truck side frame is indicated, as an entirety, by the numeral 1. In the construction illustrated, in Figs. 1 and 2, this side frame is provided with integrally cast tie strap brackets 2 that are extended in a vertical plane and projected from the lower end portions of the said side frame, inward 50 of the journal boxes. The said brackets 2 are provided with vertical slots 3. The tie

straps 4, at their inner ends, are bifurcated or split, and these split end portions are turned up and form coils or eyes 5, through which and the co-operating slots 3, nut- 55 equipped bolts 6 are passed. The slots 3 permit vertical adjustments of the tie straps, and the bolts permit the tie straps to be pivotally adjusted so as to properly engage the bottom of the journal box, not 60 shown. When the nuts 6 are tightened, the bifurcated coiled end portions of the tie strap will be frictionally clamped tightly against the embraced web of the bracket 2.

In the construction illustrated in Figs. 3 65 and 4, the cast side frame 1 is provided with a depending tie strap bracket 7, the face of which is vertically extended but integrally connected to the side frame by keepers 8. The said vertical face or web 70 of the bracket 7 is provided with a vertical slot 9, and the tie strap 10 has an inner end that is turned upward therefrom at a slight angle thereto, and is provided with a perforation through which, and the slot 9, a 75 nut-equipped bolt 11 is passed. Obviously, the slot 9 permits vertical adjustments of the tie strap 10 and the bolt 11, when tightened, securely holds the same in a desired vertical adjustment.

What I claim is:

1. The combination with a truck side frame having a tie strap bracket, of a journal box tie strap connected to said bracket with freedom for adjustments bodily, and 85 means for securing said strap to said bracket in its said different adjustments.

2. The combination with a truck side frame having a tie strap bracket, of a journal box tie strap connected to said bracket 90 with freedom for vertical pivotal movements and with freedom for vertical adjustments bodily, and means for securing said strap to said bracket in its said different adjustments.

3. A cast truck side frame having integral tie strap brackets formed with vertical slots, in combination with journal box tie straps, and bolts passed through said tie straps and the slots of said brackets and 100 adjustably connecting said tie straps to said side frame.

4. The combination with a cast truck side frame having projecting tie strap brackets formed with vertical slots, of journal box tie straps having bifurcated inner ends 5 turned into coils and embracing the co-operating tie strap brackets, and nut-equipped bolts passed through the slots of said brackets and the coiled ends of said tie

straps and adjustably connecting said straps to said brackets.

In testimony whereof I affix my signature in presence of two witnesses.

FRANKLIN L. BARBER.
